(57) **CLAIM**

I claim the ornamental design for an urinal friendly tissue dispenser, as shown and described.

DESCRIPTION

FIG. 1 is a perspective view of a partially opened urinal friendly tissue dispenser showing my new design; the broken lines depict a tissue thereof in a dispensing condition; FIG. 2 is a front elevational view thereof; FIG. 3 is a rear elevational view thereof; FIG. 4 is a side elevational view thereof, the elevational view of the opposing side being identical thereto; FIG. 5 is a top plan view thereof; and, FIG. 6 is a bottom plan view thereof.
